METHOD OF STITCHING

Thomas E. Monroe, New York, N. Y., assignor of one-half to William R. Donaldson, Northport, N. Y., and one-fourth to William R. Donaldson, as trustee; William R. Donaldson administrator of said Thomas E. Monroe, deceased

Continuation of application Serial No. 322,867, March 8, 1940. This application October 20, 1944, Serial No. 559,580.

9 Claims. (Cl. 112—262)

1

This invention relates to stitching and has more particular reference to a method of stitching. The means disclosed herein to exemplify suitable means for practicing such method is the subject of my copending application for United States Letters Patent, Serial No. 559,579 filed October 20, 1944. The present application is a continuation of my earlier filed copending application for United States Letters Patent, Serial No. 322,867, filed March 8, 1940.

An object of the invention is the provision of a novel and an improved method of stitching involving the formation in a fabric of a series of stitches of interengaging or interlocking loops of a plurality of threads at the upper, outer, or needle side of the fabric, hereinafter sometimes called the obverse side of the fabric.

Another object of the invention is so to vary the size, color, material or other physical characteristics of the different threads in the formation of such stitches that loops of a thread of a desired physical characteristic are formed at the obverse side of the fabric in regularly recurring order to produce a line of stitches which are ornamental or decorative and have a holding capacity of requisite strength to be useful in sewing.

A further object of the invention is to vary the length of loops at the obverse side of the fabric in regularly recurring order to produce a novel and an improved stitch locking effect.

Another object of the invention is so to shorten certain of the loops of such stitches that the points of concatenation with the respectively succeeding loops are disposed in positions between succeeding bights of the shortened and respectively succeeding loops in the fabric.

The invention has as a further object the production of a double loop stitch in which the loops are taken alternately from two threads and wherein the alternate loops are of different lengths.

Yet another object of the invention is to accomplish any and all of the foregoing objects with a single needle.

Other objects of the invention will become apparent in the following description which considered in connection with the accompanying drawing illustrates a preferred embodiment of the invention.

In the drawing:

Figure 1 is a view in side elevation and central vertical section of a preferred structure for carrying the method of stitching into effect;

Figure 2 is a cross-section taken substantially

2

along the lines 2—2 of Figure 1 and shows an elevation of the drive mechanism;

Figure 3 is a vertical cross-section taken substantially along the lines 3—3 of Figure 1 and shows the operating parts on an enlarged scale;

Figure 4 is a horizontal cross-section taken substantially along the lines 4—4 of Figure 3;

Figure 5 is a horizontal cross-section taken substantially along the lines 5—5 of Figure 3 and shows particularly the lower part of the machine, comprising the thread holding and loop forming mechanism;

Figures 6 and 7 are fragmentary views similar to Figure 5 and show the parts in different positions assumed in operation of the device;

Figure 8 is a vertical cross-section taken substantially along the lines 8—8 of Figure 3;

Figure 9 is a horizontal cross-section taken substantially along the lines 9—9 of Figure 8 and shows the construction of the shuttle;

Figures 10 to 14 inclusive, are views on an enlarged scale of part of the thread handling mechanism shown in Figures 5 to 7 and show the parts in the positions assumed at different stages of the operation;

Figure 15 is a schematic showing of a line of stitches, as seen from the top or obverse side of the fabric, formed by the machine in the practice of the novel method;

Figure 16 is a side view of the stitch of Figure 15, the layers of fabric being indicated by dot and dash lines;

Figure 17 is a view similar to Figure 16 but shows another form of stitch made in the practice of the novel method; and

Figure 18 is a plan view of a portion of the fabric table and shows particularly the apertures for accommodating the needle and feeding foot.

Method of stitching

In practicing the method of the invention, I arrange material to be stitched or sewed between a suitable needle at the obverse side and a plurality of threads at the reverse side of the material. The needle is of a type adapted to engage a thread, pass it through the material, and thereafter disengage or release the thread. The threads employed are identical or vary in size, material, color, and other characteristics.

The threads are selectively moved to a position for engagement by the needle as the material is advanced relative to the needle or as the needle is advanced relative to the material to produce a line of stitches. The needle engages an intermediate portion of any thread in the position of

engagement and passes the engaged thread in the form of a loop through the material being sewed from the reverse to the obverse side thereof and, after passing the first such loop of thread through the material, passes each succeeding loop of thread through the next previously formed loop of thread at the obverse side of the material to form along the obverse side of the material a line or series of interlocked loops of thread and along the reverse side of the material a line or series of substantially parallel, straight courses or lengths of thread.

By providing threads of different size, material, color, or combinations of such variations in physical characteristics of threads and selecting the thread of the desired characteristics each time a loop is to be formed, I, as shown in Figures 15 and 16, form a line of stitches of interlocked loops, along the obverse side of the material, of the various threads with the desired color, size, material, other physical characteristic, or combinations thereof, recurring in a desired sequence. Such stitches, particularly when of proper length relative to the thickness of the material being sewed, resist raveling and will firmly hold plies of fabric together. They are thus of sufficient strength and, by their formation of threads of selected characteristics as just described, are also decorative and ornamental.

The locking effect is enhanced and further variations in ornamentation are provided by shortening the loops of thread at regularly recurring intervals or in regularly recurring order. For example, in a two-thread stitch, I subject one of the threads to a greater tension than the other. When that is done, the loops of the thread under greater tension will pull the points of concatenation with the loops of the other thread to positions between the points of needle penetration through the material being sewed, or between the bights of the loops of both threads as they are passed through the material by the needle, as illustrated in Figure 17.

Various means may be employed for performing or practicing the novel method hereinbefore described. While I do not wish to be limited to any particular means, I prefer and have illustrated in the accompanying drawings the machine forming the subject matter of the above identified application Serial Number 559,579 which I have found suitable to perform and which will serve to exemplify means for performing or practicing the novel method of the present invention.

Such a machine, as shown more particularly in Figures 1 and 3, first described generally, comprises a substantially U-shaped or other suitable frame A, a needle operating head B attached to one arm of the U-shaped frame A, a thread-handling head C similarly attached to the other arm of the U-shaped frame A, a table D forming the top of the thread-handling head C, a presser foot E, and a feeding foot F adapted to cooperate with an inclined extension G of the table D to advance therealong a material or fabric arranged between the presser foot E and the table D, and a suitable needle mechanism adapted to engage a thread, pass it through the fabric, and thereafter disengage or release the thread.

In the illustrated machine, the needle mechanism comprises a reciprocable hooked or barbed needle H, a plunger I carrying the needle H attached thereto, and a pin J reciprocable within the needle H to form with the barbed or hooked end thereof an openable and closable eye in the

tip of the needle for receiving or engaging thread therein and releasing or disengaging it when open and for holding the engaged thread while passing it through the fabric. Threads from a plurality of spools K and L are selectively supplied to the needle by a shuttle M having a cam surface N, and a shoe O supported by a spring P.

Illustrative of the novel method as performed by means of the machine just generally described to exemplify suitable means for carrying out the invention, reference is made to Figures 10 to 14 inclusive. As therein illustrated the method of stitch formation involves the production of interlocked loops from a plurality of threads k and l taken from the spools K and L, in the following manner: The machine being threaded and each thread passed through one of a plurality of small holes, o, o in shoe O, as shown in Figure 10, the descending presser foot in advancing the fabric pushes the shoe O against the cam surface N into the position of Figure 11 so that the descending needle H enters the shoe to the right of the thread k as shown in Figure 11, the motion of the pin J being retarded so that the eye in the needle H is open. At this stage, the pressure of the feeding foot F against the shoe is relaxed so that the shoe returns to the position of Figure 10, as shown in Figure 12, forming a loop in the thread k within the eye of the needle. The needle upon being drawn upwards through the fabric carries the loop with it.

On the next downstroke of the needle, the eye of the needle is opened by operation of the pin J to disengage the thread above the fabric and the needle passes through the previously formed loop and the sequence of events is repeated. The tension in the thread k produced by the needle pulling on the loop, however, moves the shuttle M across so that the shoe O, on being moved toward the shuttle by the feeding foot F, now encounters the opposite side of the cam surface N, pushing the shoe into the position of Figure 13, so that the needle enters the same to the left of the thread l as shown in that figure. Upon relaxing of the pressure of the feeding foot F against the shoe, the shoe returns to the position of Figure 14 with a loop from the thread l caught by the needle. The upstroke of the needle thus draws a loop from the thread l (instead of the thread k) upward through the fabric and through the loop previously formed from the thread k. Repetition of this operation results in the formation of the stitch shown schematically in Figures 15 and 16 in which each thread, k and l, successively passes through the fabric so that the loops on the top or obverse side of the fabric, as shown in Figure 15, present the appearance of a simple chain stitch but with the loops of the chain coming from the spools in a regularly recurring order. On the reverse side the stitch presents the appearance, as shown in Figure 1, of parallel straight courses of thread, of a length equal to the combined length of the number of stitches intervening between two orderly successive stitches of the two threads. By using threads of different physical characteristics, for example, different colors, as indicated in Figure 15, the loops are formed along the obverse side of the fabric with desired physical thread characteristics recurring in an orderly or desired sequence, thus producing a stitch of decorative character.

As will be seen, the stitch of the invention possesses locking characteristics not to be found in ordinary chain stitches. In an ordinary open

chain stitch, it is often possible for the loops to disengage successively when tension along the line of stitch is applied to the fabric. This tendency, particularly when a stitch of proper length relative to the fabric thickness is employed, is largely obviated in the stitch of the invention, in which the loops come from different threads in a desired order so that tension on each thread results in catching and firmly holding each other thread engaged thereby, rather than in assisting it to ravel.

To increase the locking effect of the stitch when desired as in sewing heavy fabrics, and, whether or not an increased locking effect is desired, to provide additional variations in ornamentation, I vary the lengths of the loops formed along the obverse side of the fabric by forming relatively short loops and relatively longer loops in a regularly recurring or desired order. That is accomplished in the illustrated machine by applying different tensions on the spools of thread. The application of greater tension to the thread *l* than to the thread *k* results in the formation of shorter loops in the former, producing a reverse bend in the loop of the latter, as shown in Figure 17.

As shown at the right in Figure 17, if the thread starts to ravel in such a case, the long loop from the thread *k* falls back and is caught or strangled by the short loop of the thread *l*, thus stopping or resisting the raveling. By forming such short loops in a regularly recurring or desired order, whether or not the thread of such short loops is the same color, size, or material as that of the longer loops, I obtain a decorative effect not achieved by known stitching methods.

Drive mechanism

The illustrated machine is operated entirely by the up and down motion of a needle plunger body *I* which reciprocates through apertures *2* and *3* in a frame *4* fastened within the outer casing *5* of the needle operating head *B*. This reciprocating motion is produced through a pitman *6* attached to the upper end of plunger *I* by a bearing *7* and driven through a wrist pin *8* by a crank *9* mounted on a shaft *10*, journaled in a bushing or bearing *11* at the upper end of the head *B*. The shaft *10* is preferably driven by an electric motor (not shown) through a flexible shaft *12* in a casing *13* fastened to the frame *A* as at *14*. Only a portion of the shaft *12* and casing *13* are shown, it being understood that these are suitably connected to an electric motor which may be plugged in at any convenient outlet. The shaft *10* carries on a wheel *15* an annular gear wheel *16* driven by the shaft *12* through a pinion *17*. To permit hand operation of the machine when desired, the wheel *15* is formed with a rim *18* and carries the annular gear wheel *16* loosely within a recess formed in the wheel *15* and between the wheel and a face plate *19* affixed thereto. As best shown in Figure 2, the gear wheel *16* is formed with apertures having radial faces *20* and cam faces *21* and receiving balls or discs *22*, this arrangement constituting a unidirectional clutch. As will be understood, counter-clockwise rotation of the wheel *15* by hand unclutches the gear wheel *16* by carrying the balls or discs *22* against the radial faces *20*, thus permitting hand operation. On the other hand, counter-clockwise rotation of the gear wheel *16* forms a driving connection between the gear wheel *16* and the shaft *10* through the cam faces *21* and the discs *22*.

Variation in the stitch produced is provided for by mounting the crank *9* upon a shaft *23* af-

fixed thereto and passing eccentrically through the shaft *10*. Affixed to the other end of the shaft *23* is an arm *24* having a boss *25* adapted to enter any of a number of indentations *26* in face plate *19* and to remain therein by reason of the spring or arm *24*. By means of this arrangement, seating of the arm *24* in any of the various angular positions provided for varies the effective length of the crank *9* and thus varies the length of stitch produced.

Needle operating and fabric feeding mechanism

The needle plunger *I* bears the needle *H* fastened to it by means of a block *27* and a screw *28* and has, by reason of the crank arrangement just described, a simple reciprocatory movement. This plunger also serves, through mechanism about to be described, to impart the required movements to the feeding foot *F* and to the needle pin *J*. The needle pin *J* terminates at its upper end in a T-head *29* within a cutout *30* in the plunger *I* and feeding foot *F* is carried by a body portion *31* formed with an angle *32* adapted for engagement by the lower end of the plunger *I* and with a crosswise abutment *33* adapted to seat under an abutment *34* formed on the plunger *I* as shown in Figure 3. The body portion *31* includes also a projection *35* adapted to limit its stroke and wings *36* passing around the plunger *I* and formed with cam rises *37* adapted to engage the T-head *29*. The body portion *31* of the feeding foot *F* is pressed against the plunger *I* by means of a spring *38* fastened to the latter by screws *39*.

At the commencement of the downstroke of the plunger *I*, the feeding foot *F*, through the angle *32* and the abutment *33*, is positively carried along with it and the needle pin *J*; through the T-head *29* and the rise *37*, is also carried with the plunger. By reason of the incline of table *G*, the feeding foot is urged to the left during this downward movement, so that the angle *32* disengages from the lower end of the plunger *I*. At this time or shortly thereafter, the T-head *29* encounters a rise *40* formed in the casing *5*, disengaging the abutments *33* and *34* by pressing the feeding foot body portion *31* back against the spring *38*. Continuing motion of the plunger *I* brings the upper end of the cutout *30* against the T-head *29*, carrying the same over the rise *40* into a recess *41*, where it stops. At this point, the lower end of the pin *J* will be slightly below the level of the fabric. Meanwhile the plunger *I*, continuing to move, will have carried the lower end *42* of the spring *38*, which is slanted as shown, over the corresponding slant of the body portion *31* of feeding foot *F* just above the angle *32*, and the lower end of the plunger engaging the curve of the feeding foot *F* below the angle *32* will have wedged the feeding foot to the left out of pressing contact with the fabric.

As the upstroke of the needle commences the barb *44* of the needle *H* engages the lower end of the pin *J* closing the eye of the needle with a loop of thread therein and thereafter returning the needle pin *J* to the position of Figure 3. The feeding foot rises directly upward with the plunger *I*, being held against the same by the lower end *42* of the spring *38* (at this time below the angle *32*), until the projection *35* engages an adjustable stop *45* on the wall of the casing *5*, which engagement stops the movement of the feeding foot. The plunger *I*, however, continues to move upward until it reaches the position of Figure 3, at which point the abutment

34 slips back under abutment 33 and the angle 32 slips back under the lower end of the plunger I under the influence of the spring 38, thus returning the parts to starting position for the next stitch.

To coordinate the stroke of the feeding foot F with the stroke of the plunger I for various lengths of stitch, the stop 45 is carried on a pin 46 within a vertical slot 41 in the casing 5 and is positionable by means of a thumb nut 48 at various heights thereon to correspond with the various strokes of the plunger I produced by setting of the arm 24, as described above.

The fabric is conveniently held on the table D by the presser foot E urged downward by a weight 49 and slidably mounted on a track 50 attached to the head B by means of clips 51 and guide pins 52, the presser foot being formed with an opening 53 to permit passage therethrough of the needle and feeding foot as described.

Thread handling mechanism

The fabric supporting tables D and G, previously referred to, are formed with openings 54 and 55, respectively, under the needle and under the feeding foot (Figure 18), the former opening serving to permit passage of the needle and the latter to permit the feeding foot F to press against the fabric and therethrough against the shoe O within the head C.

As best shown in Figures 3 and 5 to 8, the shoe O is carried on a spring P fastened by means of screw 56 to a frame member 57 imbedded in the casing body 58 of the head C and is formed with a grooved upper surface 71 extending downwardly at an incline somewhat less than that of the table G so that the fabric moving down the same under the feeding foot F urges the shoe O inwardly (to the right in Figure 3), the rounded end or nose of the shoe O accordingly engaging the cam N so that the shoe is wedged to one side into the position of Figure 6 or 7, depending upon the position of the cam N. The cam N is controlled, through the shuttle M upon which it is carried, by the tension of the threads k and l passing through openings 59 and 60 at the ends of the shuttle M. The shuttle M slides back and forth on a frame 61 formed on or attached to the frame member 57 and having a cutout 62 limiting the movement of shuttle M by means of a pin 63 upon the latter. To lower friction, a wheel 64 may be mounted upon the pin 63 to furnish a riding surface for the nose of the shoe O after it has been pushed to one side or the other by the point of the cam N.

With this arrangement, it will be understood that, starting in the position of Figure 5, for example, the shoe will engage the left side of the cam N (looking toward the cam) so that the shoe will be deflected sidewise into the position of Figure 6, the needle picking up a loop from the thread k. When the shoe returns to the position of Figure 5, the needle rises and draws the loop with it, the tension created upon the thread k moves the shuttle M over to the left (looking toward the shuttle) so that the cam N is positioned on the opposite side of the shoe O in preparation for the next operation. On the next downstroke of the feeding foot, the shoe O accordingly engages the opposite side of the cam N and is deflected into the position of Figure 7 so that the needle now picks up a loop from the thread l. By this means the stitch described above, and having loops formed alternately from two threads, is produced.

Thread tensioning arrangement

The invention contemplates a very simple, but nevertheless effective method of thread tensioning. As best shown in Figures 3 and 5 to 8, the spools K and L are carried in generally cylindrical recesses formed in the body 58 of the head C and the threads k and l passing upwardly over guide surfaces 65 are given the required slight tension by reason of their wrap around the same and the consequent friction produced. The spools are held within the recesses by means of a cover plate 66 attached to the body 58 by hinges 67 and having formed with it an upper portion 68 constituting part of the table D and depending portions 69 constituting the upper side walls of the thread housing. No spindles for the spools are required, these being held in approximately the proper longitudinal position by means of bosses 70 and 71 on the body 58 and cover 66 respectively.

As it may be desired under certain conditions to produce a single thread chain stitch, I have provided means for immobilizing the shuttle M, when desired, these taking the form of slides 72 carried by means of pins 73 and slots 74 on the depending portions 69 of the cover 66. Those slides, by means of buttons 75, respectively, attached to the pins 73, may be set in the position of Figure 5 so as not to interfere with the motion of the shuttle M or either slide 72 may be slid over so as to hold the shuttle in either of its extreme positions. As will be apparent, when the shuttle is so held the shoe O will always engage the same side of cam N and accordingly a stitch will be formed from a single one of the threads k or l.

In making the stitches illustrated in Figure 17, certain of the loops are shortened relative to the length of the other loops. That is done in the novel method preferably but not necessarily by applying different tensions to the threads. For example, in the illustrated machine the tension on either thread l or k may be increased relative to the other of those threads by reversing the corresponding spool end for end. Thus as shown in Figure 8, the spool L may be reversed end for end so that it unwinds in the same direction as the spool K (counterclockwise as viewed in that figure of the drawing) the path of travel of the thread from the spool L so reversed being shown in broken lines at l'. The sharper bend around the guide 65 results in greater tension being applied to the thread from the spool L so reversed than that applied to the thread from the spool K. Consequently the loop formed of the thread from the spool L, after the succeeding loop of the thread from the spool K is passed through the first mentioned loop, is then drawn back by the tension on the thread as the cloth is advanced and by the tension produced in forming the next succeeding loop of the thread from the spool L resulting in the stitch illustrated in Figure 17 wherein the loop of the thread l is illustrated as having been shortened.

Operation

In preparing to operate the machine, the frame A, provided with a felt or rubber surfaced base 76 for that purpose, is clamped to a chair arm or table edge or other convenient location and the motor (not shown) is plugged in. The spools K and L are placed in the thread holder and the respective threads are brought through the holes 75 notches 59 and 60 and passed through the holes

in the nose of the shoe O. The wheel 15 is now turned by hand to pick up both threads and the loops above the table are pulled out with a needle or other instrument so as to bring the loose thread ends above the fabric table D, G. The fabric is now inserted under the presser foot E and feeding foot F and the machine is in condition for operation.

The length of stitch is selected by setting arm 24 to a desired position and the stop 45, by means of the thumb nut 48, is set to adjust the feeding foot motion correspondingly by means of suitable indicia (not shown) on the outside of the casing. The stop 45 may also be set with relation to the plunger I by trial, when the latter is at the upper end of its stroke. In operation, the needle plunger moves downwardly to a point where the needle is about to enter the fabric, at which time the needle pin J, being held back by rise 40 as described, opens the eye of the needle H (this releasing any loop of thread upon the needle). Shortly thereafter the feeding foot, which has been moving downwardly and to the left and thus advancing the material under the needle, is freed from its engagement with the lower end of the plunger I and the abutment 34 so that the fabric is stationary at the time the needle point enters it.

The needle, continuing to move, enters the fabric and passes through it and through the aperture 54 into the shoe O which by this time, through the action of the feeding foot F and the cam N, has been positioned to one side as shown in Figure 11. Continued motion downward of the needle plunger I results in the feeding foot F being shoved aside, permitting the shoe O to return to the position of Figure 12 and results further in the needle pin J, through its head 29 and the upper edge of the cutout 30, following the needle through the fabric to a point just above the shoe O.

During the return stroke, the hook of the needle picks up the loop of thread and the barb 44 of the needle encounters the lower end of the needle pin J, thus closing the eye of the needle about the thread. Further upward motion of the needle lifts the needle pin J so that the T-head 29 passes out of the depression 41 over the rise 40 and returns to the position of Figure 3. The feeding foot F, in the manner described above, follows the needle plunger I vertically upward to the point where the projection 35 engages the stop 45 and then stops, coming back to engagement with the plunger I under the bottom of the plunger and the abutment 34 upon the plunger completing its upward stroke.

Where the stitch of Figure 17 is desired for increasing the locking effect or for providing additional decorative effects, either spool (L, as shown in Figure 8) may be reversed end for end so that it unwinds in the same direction as the other spool (counterclockwise in Figure 8) the path of travel in this event being shown in broken lines at I'. The resulting sharper bend around the guide 65 increases the tension on the spool L as compared with spool K. In consequence, the loop formed from the spool L having first had the succeeding loop from the spool K formed through it is then drawn back by the tension on the thread as the cloth is advanced and by the tension produced in forming the second succeeding loop resulting in the stitch as shown in Figure 17. In this way by subjecting one of the threads to a greater tension than the other, loops of the thread under greater tension will pull the points

of concatenation with the loops of the other thread to points between the points of needle penetration through the fabric or between the bights of the loops of both threads as they are drawn through the fabric by the needle.

It is thought that the invention and its attendant advantages will be understood from the foregoing description, and it will be apparent that various changes may be made in the form, construction, and arrangement of the parts of the means for practicing the method of the invention, and in the particularly described steps thereof without departing from the spirit and scope of the invention or sacrificing all of its material advantages, the means disclosed being merely illustrative of suitable means for carrying out the novel method.

Having thus disclosed the invention, what I desire to secure by way of United States Letters Patent is:

1. The method of stitching which comprises reciprocating a hooked needle through a fabric from the obverse to the reverse side, advancing the said fabric in substantially equal steps between reciprocations of said needle, positioning two threads on the reverse side of said fabric for alternate loop-forming engagement in the hook of the said needle, and subjecting said threads to different tensions, whereby the loops of the thread under greater tension are shortened and those under lesser tension are correspondingly elongated to respective lengths less and greater than that of the fabric advancing steps.

2. The method of stitching which comprises reciprocating a hooked needle through a fabric from the obverse to the reverse side thereof, advancing the said fabric between reciprocations of said needle, positioning two threads on the reverse side of said fabric for alternate loop-forming engagement in the hook of said needle, and subjecting one of the threads to a greater tension than the other, whereby the loops of the thread under greater tension will pull the points of concatenation with the loops of the other thread to points between the bights of the loops of both threads as drawn through the fabric by the needle.

3. A method of stitching which comprises piercing a fabric at spaced points, engaging at one side of said fabric an intermediate portion of each of a plurality of threads in regularly recurring order, passing each thread upon engagement thereof through said fabric at one of said points to form a loop of thread at the opposite side of said fabric after each piercing thereof and through the previously formed loop of thread at said opposite side of said fabric, disengaging the thread of each such loop before next engaging any of said threads, and shortening the loops of one of said threads after each of the respectively succeeding loops is passed therethrough whereby the shortened loops of thread recur in an orderly sequence.

4. A method of stitching which comprises piercing a fabric at spaced points, engaging at one side of said fabric an intermediate portion of each of a plurality of threads in regularly recurring order, passing each thread upon engagement thereof through said fabric at one of said points to form a loop of thread at the opposite side of said fabric after each piercing thereof and through the previously formed loop of thread at said opposite side of said fabric, disengaging the thread of each such loop before next engaging any of said threads, and shortening

11

the loops of one of said threads after each of the respectively succeeding loops is passed therethrough whereby the shortened loops of thread recur in an orderly sequence, and dispose the points of concatenation with the respectively succeeding loops in positions between said spaced points.

5. A method of stitching which comprises arranging fabric to be sewed between a needle and a plurality of threads of different physical characteristics, reciprocating the needle at spaced points along the fabric from the needle side, through to the thread side, and back through to the needle side of the fabric, threading the needle at the thread side of the fabric during each reciprocation of the needle with any selected one of said threads whereby to draw a loop of thread through the fabric and a previously formed loop of thread at the needle side of the fabric and to form at the needle side of the fabric interengaging loops of threads having the physical characteristics determined by the sequence in which the needle is threaded with said threads of different physical characteristics and sequentially shortening some of the thread loops after each of the respectively succeeding loops is passed therethrough.

6. A method of stitching which comprises successively passing at equi-spaced points along fabric being sewed loops of different threads from the reverse side, through, and beyond the obverse side of the fabric and passing each succeeding loop of thread through the next preceding loop of thread while sequentially utilizing each of said different threads in said loops, varying in a regularly recurring order the length of the thread loops, and disposing the interengaged loops of threads along the surface at the obverse side of the fabric.

7. A method of stitching which comprises reciprocating a single needle at spaced points along fabric being sewed through the fabric from the obverse, to the reverse, and back to the obverse side thereof, threading the needle at the reverse side of the fabric and unthreading the needle at the obverse side of the fabric during each reciprocation of the needle with any selected one of a plurality of different colored threads whereby to draw a loop of thread through the fabric and each succeeding loop of thread through a preceding loop of thread at the obverse side of the fabric, sequentially varying the length of the loops by shortening certain of them after each

12

loop to be shortened is drawn through the fabric, and disposing the interengaged loops of different colored threads along the surface at the obverse side of the fabric in a color sequence determined by the order of selection utilized in threading the needle.

8. A method of stitching which comprises passing a loop of a thread at one side of a fabric through to the other side thereof, moving said fabric while holding said loop to arrange it along the fabric, passing a second loop equal in length to the first said loop and of a different thread through the fabric and the first said loop, moving said fabric the same distance as it was moved after the passage therethrough of the first said loop while holding said second loop to arrange it along the fabric, and repeating the foregoing steps while applying sufficient tension to said different thread to decrease the length of each said second loop along the fabric to less than the distance of the fabric movement.

9. A method of stitching which comprises successively passing loops of thread of equal predetermined length from different threads at one side of the fabric therethrough and after the first loop through the respectively next preceding loops at the other side of said fabric, moving said fabric in steps of equal length after each loop is passed therethrough while holding said loop to dispose it along the fabric, and shortening the length of certain of the loops to less than the length of the steps of fabric movement while the respective succeeding loops are being passed therethrough whereby correspondingly to elongate said respectively succeeding loops.

THOMAS E. MONROE.
